UNITED STATES PATENT OFFICE.

ROBERT B. SMITH, OF SARGENT, NEBRASKA, ASSIGNOR OF ONE-HALF TO GEORGE E. STEINHOFF, OF SARGENT, NEBRASKA.

COMBINED MAIL BOX AND SIGNPOST.

Application filed April 9, 1927. Serial No. 182,466.

The invention relates to a combined mail box and sign post.

The object of the present invention is to provide a simple, practical and efficient combined mail box and sign post of strong, durable and comparatively inexpensive construction adapted to be mounted beyond the roadway so as to be out of the way of ditching, grading and other road working machinery and equipped with a service arm adapted to support a mail box and a sign adjacent the roadway in as convenient and advantageous position as when mail boxes and sign posts are arranged in the ordinary position adjacent the crown of the road.

In various sections of the country mail box posts and highway sign posts are driven into the ground at the edge of the ground of the road and inside the ditch at the side of the road. When in this position they are continually in the way of traffic and constantly in the way of road working machinery. On dirt roads it is necessary to go over the road every week in the year and if there is much rain the road must be gone over several times in a week. The present arrangement of highway sign post and mail box post causes the traffic to pull the drag up out of the ditch and around these posts and it is necessary to repeat this operation many times in a mile and it becomes a real nuisance. Also the work of cleaning up the ditches at these posts must be done with shovels by hand and this is very expensive. In addition to this, about twice each year a large grader must work the road and ditches over and at such times it is necessary to pull out these mail box posts and highway sign posts and remove them, replacing them when the work is done. This is slow, inconvenient and expensive.

A further object of the invention is to provide a combined mail box and highway sign post adapted to be driven into the ground or otherwise arranged for use at a point outside of the ditch and up on the curb clear of all road working machinery and where it will not be an obstruction at any time during the year.

Another object of the invention is to provide a combined mail box and sign post of this character equipped with an adjustable pivotally mounted service arm adapted to carry both a mail box and a road sign and

capable of supporting the sign and the mail box at the desired elevation at the side of the roadway and capable of being swung horizontally out of the way and into a position in parallelism with the roadway or vertically to an upright position where the conditions are such that will not permit of a horizontally swinging of the service arm.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:—

Figure 1 is a side elevation of a combined mail box and sign post constructed in accordance with this invention.

Fig. 2 is a front elevation of the same the service arm being shown swung horizontally out of the way in dotted lines.

Fig. 3 is a vertical longitudinal sectional view, the service arm being elevated out of the way.

Fig. 4 is a transverse sectional view illustrating the construction of the locking mechanism for securing the pivoted brace to the adjustable service arm.

Figs. 5 and 6 are detail views.

In the accompanying drawings in which is illustrated the preferred embodiment of the invention the combined mail box and sign post comprises in its construction a post 1 preferably constructed of tubular metal circular in cross section as shown, but a solid post may, of course, be employed if desired. The post 1 has its lower end 2 flattened and bifurcated to receive a tapered blade 3 secured in the slot 4 of the bifurcation by a rivet 5 or other suitable fastening device. The tapered blade which projects laterally from opposite sides of the post is adapted to readily penetrate the ground and the lower flattened end 2 is tapered in thickness to provide oppositely inclined side faces which substantially merge into the side faces of the lower portion of the blade so as to form no obstruction in driving the post into the

ground. The post may be set in concrete or mounted in any other desired manner as will be readily understood.

- Mounted upon the upper portion of the post is a sleeve 6 having its upper end split and spread to form a pair of divergent arms 7 which are pivoted between spaced longitudinal side flanges 8 of a service arm 9 by a transverse bolt 10 or other suitable pivot.
- 10 The arms 7 are rounded at their upper ends at the inner side edges at 11 and form shoulders 12 adjacent their outer side edges to limit the downward movement of the service arm for supporting the same in a horizontal position.
- 15 The rounded inner edges permit the service arm to swing upwardly from a horizontal or approximately horizontal position to the upright position illustrated in Fig. 3 of the drawings. The transverse pivot 10 is located intermediate of the ends of the service arm or member and the inner portion is preferably about one-third the length of the outer portion although the service arm or member may be varied in length to suit
- 20 the width of the ditch at the side of the road. In practice three standard sizes will be employed to suit the different road construction, but a service arm or member of any suitable length may, of course, be provided.
- 25 The service arm is rigidly held in its adjusted position by means of an inclined brace 13 pivoted at its lower end by a bolt 14 between extended ends 15 of a collar 16 encircling the lower portion of the sleeve and
- 30 having the terminal portions 15 bent outwardly to form spaced ears. The upper portion of the inclined brace 13 is forked to form arms 17 which are arranged at an obtuse angle to the body portion of the brace.
- 35 The arms 17 fit against the other faces of the side flanges 8 of the service arm and are provided at their upper ends with inwardly extending lugs 18 which project inwardly over the arm as clearly illustrated in Fig. 4
- 40 of the drawings. The flanges 8 are provided with approximately inverted key hole shaped openings 19 to receive a transverse fastening device 20 of substantially the same shape in cross section as the openings 19
- 45 and provided at one end with a handle 21 and having reduced rounded bearing portions 22 to permit the transverse fastening device to be partially rotated to carry the transverse fastening device out of alignment
- 50 with the openings 19 to prevent the fastening device from becoming accidentally withdrawn from engagement with the flanges and the brace. The rounded portions of the transverse fastening device permit the latter
- 55 to be partially rotated to align the fastening device with the openings and in this position the handle is in an upright position so that the handle will operate as a weight to swing the transverse fastening device out
- 60 of alignment with the key hole openings
- 65

should the person adjusting the brace and the service arm omit to turn the handle down to its locking position. The key hole openings 19 of the flanges are arranged in transverse alignment and at suitable intervals to 70 permit the service arm to be adjusted to a horizontal or slightly inclined position for use and to be arranged in an upright position when it is desired to move the service arm out of the way of grading or other road 75 making machinery and when it is impractical to swing the arm horizontally to accomplish this result. The sleeve is provided at its lower end at diametrically opposite points with four notches 23 which are 80 adapted to engage with the projecting ends of a pin 24. The pin 24 pierces the post and projects from opposite sides thereof and is suitably secured to the post to form the projecting studs to interlock 85 with the notches of the lower end of the sleeve. By lifting the sleeve out of engagement with the pin the sleeve and the service arm are adapted to be rotated to extend the service arm across the ditch of a road or to 90 arrange it longitudinally of the ditch at the outer side thereof. When the sleeve is in engagement with the pin it is held against accidental rotary movement.

The outer end of the service arm is provided with a depending portion 25 which is adapted to receive a road sign. The road sign which may be of any desired construction is designed to be secured to the depending portion 25 by one or more bolts or other suitable fastening means. The outer end portion of the service arm is also adapted to support a mail box 26 fitted against the lower edges of the side flanges 8 and secured to the arm by clevises 27. The clevises or clips 27 are approximately U-shaped and have threaded terminals for the reception of butts 28 for securing clip plates or bars 29 to the threaded ends of the clips. The plates or bars 29 extend across the lower face of the mail box and support the latter which is securely clamped against the lower edges of the side flanges of the service arm so that there is no liability of a mail box accidentally slipping out of proper position. The inner end of the service arm is provided with a suitable counterbalancing weight 30 which substantially counterbalances the weight of the mail box and the road sign when the former is empty and it enables the service arm to be readily shifted and adjusted. The device is designed to be constructed of galvanized iron or other suitable material and will present a neat and attractive appearance, also the parts of the device may be 110 readily separated for convenience of shipping and may be quickly assembled for use.

The combined mail box and sign post may be used for supporting either the mail box or a sign, that is the depending sign support- 120
